MOTOR DRIVEN PAPER DISPENSER

Morris D. Bandler, 16 Kenwood Drive, New Rochelle,
N.Y., and James F. G. Bowlby, Rte. 23 and Boonton
Ave., Butler, N.J.

Filed May 24, 1963, Ser. No. 75,061

Term of patent 14 years

(Cl. D52—2)

FIG. 1

Des. 198,758

PAGE 2

FIG. 2

FIG. 1 is a front perspective view taken from the top and one end of a motor driven paper dispenser embodying our new design, the rear being substantially plain and unornamented; and

FIG. 2 is an elevational view taken from the end opposite that shown in FIG. 1, the bottom being essentially flat except for the two legs.

We claim:

The ornamental design for a motor driven paper dispenser, as shown and described.
